UNITED STATES PATENT OFFICE

2,403,334

ELECTRIC WATER HEATER

Ralph A. Blanchard, Portland, Oreg.

Application May 20, 1944, Serial No. 536,502

1 Claim. (Cl. 219—40)

1

This invention relates generally to the heating of liquids and particularly to an electric water heater.

The main object of this invention is to construct a water heater whereby water may be heated as drawn from a supply system without the necessity of storing same in a tank or employing electric energy at a rate not obtainable from the ordinary lighting circuit.

The second object is to produce a heater of the class described which will occupy a minimum amount of space and can be enclosed within a wall space or mounted on a plumbing fixture without presenting an objectionable appearance or being in the way.

The third object of this invention is to produce a heater of the class described in which the fluid being heated is employed as a resistor and circuit closer, and in which means is included for adapting the device to various types of water, that is as far as the mineral content thereof is concerned.

I accomplish these and other objects in a manner set forth in the following specification as illustrated in the accompanying drawings, in which:

Fig. 1 is a plan of the device.

Fig. 2 is a vertical section taken along the line 2—2 in Fig. 1.

Fig. 3 is a vertical section taken along the line 3—3 in Fig. 1.

Fig. 4 is a horizontal section taken along the line 4—4 in Fig. 3.

Fig. 5 is a horizontal section taken along the line 5—5 in Fig. 3.

Fig. 6 is a horizontal section taken along the line 6—6 in Fig. 3.

Similar numbers refer to similar parts throughout the several views.

Referring in detail to the invention, there is shown a base 10 having a depending body 11 provided with a vertical passageway 12 which is controlled by the needle valve 13 whose threaded stem 14 is provided with a lock nut 15. The body 11 is provided with a threaded cap 16 for the purpose of discouraging tampering with the setting of the valve 13. Cold water is admitted to the body 11 by means of the supply pipe 17.

Also depending from the base 10 is a hot water manifold 18 to which is connected the open hot water pipe 19. It will be understood that the pipe 19 is not valved but must be open to the atmosphere at all times.

Depending from the center of the body 10 is a boss 20 which is tapped to receive the vertical

2

clamping bolt 21. The upper end 22 of the passageway 12 is somewhat enlarged.

Resting upon the base 10 and surrounding the bolt 21 is the hard rubber or plastic cup 23, whose bottom 24 is provided with an annular groove 25 having an outlet opening 26, which communicates with the opening 27 in the manifold 18 through which hot water escapes through the pipe 19. The bottom 24 has a boss 28 on its under side which fits into the opening 22 and serves to locate the parts 10 and 23 with relation to each other. A gasket 29 is interposed between the members 10 and 24 around the boss 28.

The cup 23 has a tubular center 30 which extends somewhat above the sides of the cup 23 and through which center the bolt 21 extends.

Outside of the annular groove 25 and close to the interior of the cup 23 is a tapering passageway 31 which passes through the boss 28. A tubular casing 32 surrounds the cup 23 and extends somewhat above its outer edge. A conical carbon electrode 33, having a tubular metallic liner 34 is mounted on the center 30 and has disposed above and below same the metallic washers 35. These washers are interchangeable to vary the vertical position of the electrode 33 by merely varying the number of washers under the electrode.

Surrounding the electrode 33 and spaced therefrom is an outer carbon electrode 36 whose conical interior 37 converges downwardly to the outer circumference to the groove 25. The electrode 36 rests upon the bottom 24. The electrode 36 is enclosed within the metallic casing 38, which is spaced from the inner surface of the cup 23. The space 39 between the members 23 and 38 communicates with the passageway 31 through which cold water enters the device. The casing 38 extends above the electrode 36 to a cover plate 40, which also rests upon the upper edge of the cup 23. The portion of the casing 38 above the cup 36 is provided with openings 41 through which water can pass from the space 39 downwardly through the clearance space 42 between the electrodes 33 and 36.

Over the cover plate 40 is placed a head 43 in which are embedded the binding posts 44 and 45, the uppermost portions of which are embedded in the cap 46, which is held in place by a collar 47 and the clamping nut 48 on the bolt 21. A ferrule 49 extends across the junction of the members 43 and 46. Secured to the binding posts 44 by means of a screw 50 is the bus bar 51, which is integral with or secured to the casing 38.

Secured to the binding posts 45 by means of the screw 52 is the washer 53 which rests on the uppermost washer 35. An insulating disc 54 separates the washer 52 and the bus bar 51.

Channels 55 are formed between the members 43 and 46 to admit the leads 56 from a power line. The leads 56 are secured to the binding posts 44 and 45 by means of the set screws 57.

Numerous devices are on the market for heating water electrically, some of which employ water as a resistor. However, such devices have not proved satisfactory owing to the variation in the mineral content of the water in various localities requiring a great variety of electrode sizes. With the construction above described, it is only necessary to move the washers 35 above or below the electrode 33 in order to vary the gap formed by the space 42 until the desired heating rate is obtained. This adjustment in conjunction with the setting of the needle valve 13, enables the user to control the temperature of the water and draw from the outlet the maximum amount of water heated to the desired temperature.

While I am aware that the principle of utilizing a fluid as a circuit closure in the form of a resistance which will heat the fluid passing therethrough, is old, and I do not intend to cover such devices broadly but I do intend to cover such modifications as fall fairly within the appended claim and which are directed to my improvements over the prior art.

I claim:

- 10 In a device of the class described, a combination of a cup of insulating material having an outer cylindrical electrode disposed therein, the interior of which is conical, a central conical electrode whose exterior is spaced from the interior of the outer electrode, means for adjusting the axial relationship of the two electrodes, a valved orifice in the bottom of said cup adapted to control the flow of water through the space around the outer electrode, and means for supplying current to said electrodes when water bridges the gap therebetween.
